A. H. BROWN, OF SPRINGFIELD, VERMONT.

Letters Patent No. 64,279, dated April 30, 1867.

IMPROVED MEAT-HAMMER.

The Schedule referred to in these Letters Patent and making part of the same.

TO ALL WHOM IT MAY CONCERN:

Be it known that I, A. H. Brown, of Springfield, in the county of Windsor, and State of Vermont, have invented a new and improved Meat-Hammer; and I do hereby declare that the following is a full, clear, and exact description thereof, which will enable others skilled in the art to make and use the same, reference being had to the accompanying drawings, forming part of this specification.

This invention relates to a new and improved hammer for pounding meat, in order to render the same tender; and it consists in having the face or faces of the hammer provided with one or more annular, sharp, or V-shaped edges, as hereinafter fully shown and described, whereby the meat will not only be made tender, but the juices of the meat also retained in it. In the accompanying sheet of drawings—

Figure 1 is a side sectional view of my invention, taken in the line $z z$, fig. 2.

Figure 2, an end view of the same.

Similar letters of reference indicate like parts.

A represents the hammer, and B the handle thereof. The handle may be of wood, and the hammer of metal, cast or wrought iron, or steel; cast iron will probably answer the purpose. This hammer is provided with two faces, one at each end. This is not strictly necessary, but it may as well have two faces as one, as two faces will not augment the cost of manufacture. These faces are provided with one or more annular V-shaped or sharp edges, $a a'$. Two of such edges are shown on each face, and this probably would be the most desirable number. These annular edges, under the force of the blows, sink into the meat, and bruise it so as to render it tender, and at the same time form channels or recesses to receive the juices of the meat.

This is an important feature, as in other-hammers and devices for this purpose no provision is made to retain the juices. The corrugated pressure-rollers allow all the juices to escape, and the corrugated-faced hammers in use form perfect escape-channels for the escape of juices.

Having thus described my invention, I claim as new, and desire to secure by Letters Patent—

A meat-hammer having its face or faces provided with one or more annular edges, substantially as and for the purpose herein set forth.

The above specification of my invention signed by me this 4th day of February, 1867.

A. H. BROWN.
